BUMPER SWITCH

Harry E. Williams and Lyndon A. Durant,
Chicago, Ill.

Application March 31, 1939, Serial No. 265,117

8 Claims. (Cl. 200—52)

This invention has as its principal object the provision of an improved bumper switch for use in amusement apparatus such as bagatelle games and the like which include a playing surface over which a ball or other projectile is propelled for engagement with various rebound devices and hazards, the bumper switch of the present invention constituting such a rebound device or hazard.

10 Viewed from another aspect, the invention provides an improved bumper switch which is of simplified construction and adapted to be assembled as a unit for convenient and expeditious mounting on the playing board.

15 A particular object of the invention is the provision of an improved bumper switch including an elongated support adapted to be mounted in upright position on a playing board, a coil spring pendently mounted from an upper end of the support so as to freely surround the same, the support being conductive to establish electrical contact with the spring and there being a second conductive sleeve contact surrounding the lower portion of the support and carried by the latter on insulation means mounted on the support, the lowermost end of the spring being looped to surround the second contact so that the spring may be pushed toward the support from any radial direction to complete a circuit through the spring and the second contact sleeve.

30 A further object is the provision of means for establishing electrical connection with the second sleeve contact.

Other objects and advantages peculiar to the invention reside in certain details of construction and the arrangement of parts described hereinafter in view of the annexed drawing, in which:

Fig. 1 is a perspective view of a bumper switch mounted on a playboard;

Fig. 2 is an enlarged, partly sectionalized, exploded perspective of the device of Fig. 1;

Fig. 3 is a vertical section along line 3—3 of Fig. 1 and including a circuit diagram; while

Fig. 4 is a horizontal section along line 4—4 of Fig. 3.

In general, the preferred form of the device shown in Fig. 1 includes a coil spring 10 pendently mounted from its upper end portions on an upright mounting post 11 which is seated in the playboard 12 so as to extend at right angles to the upper surface, there being a suitable dome piece or cap 13 of plastic or other material secured as a finish piece to the upper end of the post. The mounting post 11 is conductive and

is provided with a second contact sleeve 14 which is fitted over an insulating sleeve 15 (Figs. 2 and 3) with its lower end portion resting on a combination mounting and contact plate 16. The lowermost end of the conductive spring 10 is turned back to provide a central contact eye or loop 17 which loosely surrounds the second contact member or sleeve 14. By pressing against the spring, the contact loop 17 may be made to engage the contact sleeve 14 and complete a circuit for any kind of signal device and control mechanism utilized in conjunction with the amusement apparatus which employs the playboard 12.

In its more detailed structural features as shown in Fig. 3, the mounting post 11 has a reduced shank portion 11a which fits through the insulating sleeve 15 and extends with the latter through the board 12 for engagement with a mounting nut 18. The juncture of the shank portion with the main upper part 11 of the post provides a shoulder 11b which bears against an insulating washer 19, which in turn bears against the insulating sleeve 15 and the outer contact sleeve 14 so that when the mounting nut 18 is drawn up, the lower end of the sleeve 14 will be tightly drawn against the contact plate 16. The contact plate 16 serves both as a means for establishing electrical connection with the sleeve 14 and as a means of stabilizing the mounting of the entire unit on the board to prevent the lower end of the sleeve from biting into the latter. In some installations the plate 16 may be omitted and connection established directly with the sleeve 14. Electrical connection with the second or sleeve contact may be established by a conductor 20 which is passed loosely through a hole 21 cut in the board and has its end portion soldered or otherwise secured to the under side of the plate 16. In order to assure good electrical contact the lower contact loop 17 of the pendent spring is provided with a conductive grommet 17a (Figs. 2 and 3).

The assembly of the bumper unit is completed by the provision of a central loop 25 at the upper end of the spring and which is adapted to fit over the threaded upper end 11c of the post 10 against a stabilizing mounting plate 26 which rests against the shoulder formed between the main part of the post 11 and the reduced threaded portion 11c. A clamping washer 27 is fitted against the central mounting loop 25 so as to clamp the latter against the plate 26 and the shoulder on the post when the dome piece or

cap 13 has its threaded bore 13a turned onto the end 11c of the post.

- As illustrative of one application of the device for control purposes in an amusement apparatus, the circuit diagram of Fig. 3 is depicted and includes an electrically energized instrumentality such as the relay 30 connected by a conductor 31 to a connecting lug 32 engaged on the lower end of the mounting post by the nut 18. The remaining terminal of the relay is connected by conductor 33 to one side of a power source or battery 34, the remaining terminal of the battery being connected by conductor 35 to the lead 20 soldered to the mounting plate 16. In operation, as shown in Fig. 3, a ball 36 rolling over the board 12 may engage the side of the spring 10 and move the latter in a radial direction toward the mounting post so as to cause the central contact ring portion 17-17a to bear against the sleeve 14, thus closing a circuit which leads via conductor 31 through the post 11, the upper end loop 25 of the contact spring and through the lower loop contact portion 17-17a, the sleeve 14, the mounting plate 16, conductors 20-35, and the battery so as to energize the relay 30 so long as the ball urges the contact loop against the second sleeve contact. Preferably, the resiliency of the spring is calculated to effect a more or less positive rebound of the ball therefrom to enhance the bumper action of the device.

The objects and advantages of the invention may be realized in variant forms of the particularly described illustrative embodiment, and the invention is therefore not confined to the details recited herein for purposes of explanation except as may be provided in the appended claims.

Having thus described our invention, what we claim as new and desire to protect by Letters Patent is:

1. A bumper switch including a conductive mounting post adapted to be mounted in upright position on a playing surface, a conductive sleeve mounted to surround a portion of said post in insulated relation with the latter, a conductive coil spring mounted at its upper end at the upper end portion of said post so as to surround the latter loosely for movements in a substantially radial sense toward the post, the lower end portion of said spring having a centrally disposed loop loosely surrounding said conductive sleeve on the post and normally out of contact with the latter, said loop contacting said sleeve to complete an electrical circuit when the spring is moved a predetermined amount toward the post.

2. A bumper switch including a conductive mounting post adapted to be mounted in an upright position on a playboard, an insulating sleeve arranged on said post, a conductive sleeve contact fitted onto said insulating sleeve, a conductive spring pendently mounted from one of its ends on the upper end portion of said post and loosely surrounding the latter, a lower end portion of said spring being turned back upon itself to provide a central contact loop loosely surrounding said conductive sleeve and normally spaced out of contact with the latter, said post and sleeve being adapted for connection in a control circuit which is closed by movement of the spring toward the post a predetermined amount to cause said contact loop to bear against the sleeve.

3. A bumper switch including a conductive post having a shoulder formed between its ends, a portion thereof at one side of said shoulder con-

stituting a mounting shank adapted to extend into a mounting surface, an insulating sleeve on said mounting shank, a conductive sleeve fitted over said insulating sleeve and bearing against means providing an insulating spacer between an end of the conductive sleeve and said shoulder on the post, a conductive mounting plate fitted over said insulating sleeve against an opposite end of said conductive sleeve and adapted to rest on said mounting surface, the portion of said shank extending into said mounting surface being drawn tightly into the latter whereby said conductive sleeve is clamped tightly between said conductive plate and the shoulder portion of the post, said post and plate being adapted for connection in a control circuit, said post having a shoulder portion at its end opposite said shank, a conductive coil spring clamped between members mounted on said last-mentioned shoulder portion so as to be suspended pendently in loosely surrounding relation to the post, said spring having an end portion looped loosely around said conductive sleeve and normally out of contact with the latter and adapted to be engaged with the conductive sleeve to close said circuit by pressure applied to the spring in a direction toward the post.

4. In a bumper switch of the type including a mounting post adapted for mounting in an upright position on a mounting surface and a conductive coil spring pendently mounted from an upper end of the post to surround the latter loosely, contact means including a conductive sleeve member and means insulatingly mounting the same on said post in the region of the end of said spring opposite its pendent mounting, said end of the spring being looped to freely surround said sleeve out of contact therewith, pressure applied against said spring in a direction toward said post being effective to move the spring and cause said loop to bear against said sleeve and establish electrical connection therewith, said post and sleeve being adapted for connection in a control circuit.

5. A device of the class described including a conductive mounting post having a reduced shank portion, an insulating washer fitted over said shank portion against the shoulder formed between the juncture of the latter and the remaining part of the post, an insulating sleeve fitted over said shank against said washer, a conductive sleeve fitted over said insulating sleeve against said washer, said shank portion being arranged and constructed to extend into a mounting member to urge said conductive sleeve against said washer and secure the post in a predetermined mounted relation with said member, and a conductive coil spring pendently mounted from the end portion of said post opposite said shank and a contact ring arranged at an end of said spring to surround said sleeve in normally spaced relation thereto, said spring being movable in a general direction toward said post to cause said ring to engage said conductive sleeve to close a control circuit through the conductive sleeve, and post.

6. A device of the class described including a conductive mounting post having a shoulder formed thereon between its ends, a conductive sleeve on the mounting post and means on said post insulating said sleeve from the post and shoulder, movement of said sleeve in one axial direction on the post being limited by said shoulder, a conductive coil spring pendently mounted from one of its ends on an end portion

- of said post remote from said sleeve, said spring having a contact ring portion formed at its opposite end and normally surrounding said sleeve in spaced relation thereto, pressure against said 5 spring in the general direction of said post being effective to move said contact ring into conductive engagement with the sleeve to close a control circuit, connections with said control circuit being established through said post and conductive 10 sleeve.
7. A bumper switch including a standard, a helical contact spring mounted on the standard with its convolutions surrounding the same in spaced relation thereto and arranged to yield to 15 a pressure applied thereto in a direction generally toward the standard, stationary contact means carried by said standard and extending around the same substantially concentrically of said standard and helical spring and near an end 20 of the latter, and contact means arranged at said end of the spring around said stationary contact means normally out of engagement therewith and

adapted to conductively engage the same when said helical spring is moved toward the standard as aforesaid, said contact means on the spring and said stationary contact being adapted for connection in a control circuit. 5

8. A bumper switch including a supporting post, a conductive coil spring and means mounting the same with convolutions surrounding said post in spaced relation therewith for movement of said convolutions in a general direction toward the 10 post, contact means arranged around said post near an end of said spring, and a second contact means arranged at said end of the spring to surround said first-mentioned contact means in normally spaced relation thereto and adapted to 15 conductively engage said first-mentioned contact means when pressure is exerted against any of said convolutions in a direction generally toward said post. 15
